STATUETTE BASE

Emil Avrack, Brooklyn, N.Y.

Filed May 23, 1960, Ser. No. 60,693

Term of patent 7 years

(Cl. D29—23)

FIG. 1

FIG. 3

FIG. 1 is a front elevational view of a statuette base, showing my new design.

FIG. 2 is a top plan view of FIG. 1.

FIG. 3 is a side elevational view of one end of the base.

The broken line showings are for illustrative purposes only.

I claim:

The ornamental design for a statuette base, as shown and described.
